US00D531638S

(12) **United States Design Patent** (10) **Patent No.:** **US D531,638 S**
(45) **Date of Patent:** **** Nov. 7, 2006**

(54) **ENGINE ASSEMBLY**

(75) Inventors: **Christopher J. Drew**, New Berlin, WI (US); **Charles Lasky**, Grafton, WI (US); **Paul A. Leech**, Fox Point, WI (US); **John P. McDonald**, New Berlin, WI (US); **Brian P. Saita**, Milwaukee, WI (US); **John R. Schneiker**, Muskego, WI (US); **Kipp K. Stevens**, Fox Point, WI (US); **Christina E. Wisler**, Waukesha, WI (US)

(73) Assignee: **Briggs & Stratton Corporation**, Wauwatosa, WI (US)

(**) Term: **14 Years**

(21) Appl. No.: **29/231,995**

(22) Filed: **Jun. 13, 2005**

(51) **LOC (8) Cl.** **15-01**

(52) **U.S. Cl.** **D15/1**

(58) **Field of Classification Search** D15/1-5;
123/41.7, 50 A, 198 E, 306, 308, 657, 661,
123/667

See application file for complete search history.

(57) **CLAIM**

The ornamental design for an engine assembly, as shown and described.

DESCRIPTION

FIG. 1 is a front perspective view of an engine assembly of the present invention.

FIG. 2 is a top view of the engine assembly of FIG. 1.

FIG. 3 is a bottom view of the engine assembly of FIG. 1.

FIG. 4 is a front view of the engine assembly of FIG. 1.

FIG. 5 is a rear view of the engine assembly of FIG. 1.

FIG. 6 is a left side view of the engine assembly of FIG. 1; and,

FIG. 7 is a right side view of the engine assembly of FIG. 1.

1 Claim, 7 Drawing Sheets
